UNITED STATES PATENT OFFICE

WILLIAM C. CHAPMAN, OF CHICAGO, ILLINOIS

DESIGN FOR A TIE-BACK FOR DRAPES, CURTAINS, AND THE LIKE

Application filed April 9, 1932. Serial No. 43,445. Term of patent 14 years.

To all whom it may concern:

Be it known that I, WILLIAM C. CHAPMAN, a citizen of the United States, residing at Chicago, in the county of Cook and State of Illinois, have invented a new, original, and ornamental Design for a Tie Back for Drapes, Curtains, and the like, of which the following is a specification, reference being had to the accompanying drawing, forming a part thereof.

In the said drawing, the figure is a plan view of a tie back for drapes, curtains and the like showing my design.

I claim:

The ornamental design for a tie back for drapes, curtains and the like as shown.

In testimony whereof, I hereto subscribe my name this 24th day of March, A. D. 1932.

WILLIAM C. CHAPMAN.
